US0D1061614S

(12) **United States Design Patent** (10) **Patent No.:** **US D1,061,614 S**
(45) **Date of Patent:** **** Feb. 11, 2025**

(54) **DISPLAY SCREEN WITH GRAPHICAL USER INTERFACE**

(71) Applicant: **ConsumerDirect, Inc.**, Irvine, CA (US)

(72) Inventors: **David B. Coulter**, Tustin, CA (US);
Samantha Gina Marie Trovato, Costa Mesa, CA (US)

(73) Assignee: **ConsumerDirect, Inc.**, Irvine, CA (US)

(***) Term: **15 Years**

(21) Appl. No.: **29/881,875**

(22) Filed: **Jan. 6, 2023**

(51) **LOC (15) Cl.** **14-04**

(52) **U.S. Cl.**

USPC **D14/494**; D14/485

(58) **Field of Classification Search**

USPC D14/489-495, 485-488

(57) **CLAIM**

The ornamental design for a display screen with graphical user interface, substantially as shown and described.

DESCRIPTION

The Sole FIGURE is a front view of a display screen with graphical user interface showing our new design.

The outermost broken lines showing an electronic device form no part of the claimed design. The innermost broken line rectangle showing a display screen or portion thereof forms no part of the claimed design. The remaining broken lines showing the graphical user interface form no part of the claimed design.

1 Claim, 1 Drawing Sheet
